UNITED STATES PATENT OFFICE.

GUSTAV EHRHARDT, OF EISENACH, GERMANY.

MEANS FOR SECURING CENTER PIVOTS TO AXLES IN GUNS.

SPECIFICATION forming part of Letters Patent No. 700,633, dated May 20, 1902.

Application filed January 8, 1902. Serial No. 88,914. (No model.)

To all whom it may concern:

Be it known that I, GUSTAV EHRHARDT, engineer, a citizen of the United States, residing at Eisenach, in the Grand Duchy of Saxe-Weimar, German Empire, have invented certain new and useful Improvements in Means for Securing Center Pivots to Axles in Guns, of which the following is a specification.

My invention relates to a means for securing the center pivot in guns. As compared with an arrangement hitherto known, in which the center pivot is secured by means of balls which at the same time serve as bearing-balls, the present arrangement possesses the advantage that the strong upward thrust arising while the gun is traveling is safely taken up by a large flat surface.

The invention is illustrated in the annexed drawings, wherein—

20 Figure 1 shows a lateral elevation in section of a gun with the center-pivot-securing arrangement. Fig. 2 is a longitudinal section through the center-pivot bearing or socket. Fig. 3 is a cross-section through the same, and Fig. 4 a securing-segment in plan and cross-section.

The pivot *a* is provided with a peripheral groove, which, as illustrated in the accompanying drawings, is of rectangular section *b*. The pivot-bearing *c* has a similar groove (see Fig. 2) at the same level. At a suitable point the side of the bearing is provided with an internally-screw-threaded hole *e*. This hole is closed by the plug *f*, screwed into it, and serves 35 for the introduction of the various segments *g* into the recess formed by the two grooves, one half of each segment being contained in the groove in the socket and the other half in that of the center pivot. The segments are 40 introduced into the hole one by one. Hence the diameter of the hole must correspond to the size of one segment. The segments when all are inserted form a complete ring, as shown in Fig. 3, so that after the hole *e* has been 45 closed by the plug *f* the pivot cannot be lifted out of its socket. In the drawings the segments are shown of rectangular section. On their outer surface facing away from the center pivot each segment has an internally-

screw-threaded hole *h*, Fig. 4, to facilitate its 50 removal from the bearing. Instead of the segments cubical or rectangular blocks might be employed.

If a ball-bearing is employed, on account of the violent jerks or concussions in traveling 55 the balls would be likely to get flattened and would jam when the upper gun-carriage is turned. By securing the center pivot in the manner described the upper gun-carriage slides with its bearing-surface *i* on the slide-face *j*, and the surfaces of the segments which have to bear the strain of the concussion in traveling are not utilized as bearing-surfaces, while at the same time the complete ring formed by the segments replaces the portion 60 of the bearing-surface lost on account of the recess. Owing to the flat pressure-surface thus created the segmental ring can safely take up the thrusts of jolts without any risk of damage to the faces of the ring and pivot 70 taking up the strain.

Having now particularly described and ascertained the nature of my said invention and in what manner the same is to be performed, I declare that what I claim is—

75

1. Means for securing the center pivot of guns consisting of a ring formed of separable segments seated in a space formed by grooves in the center pivot and pivot-bearing, substantially as described.

80

2. Means for securing the center pivot of guns consisting of a center pivot provided with a peripheral groove, a pivot-bearing having a groove opposite the peripheral groove, and a ring formed of separable segments 85 seated in the space formed by said grooves, substantially as described.

3. In a pivot-bearing for guns, a pivot having a peripheral groove, a pivot-bearing having a groove opposite said peripheral groove 90 and an orifice in the pivot-bearing for admitting segments into the space formed by said grooves, for forming a segmental ring therein, substantially as described.

4. A pivot-bearing for guns comprising a 95 pivot provided with a peripheral groove, a pivot-bearing provided with a groove opposite said peripheral groove, an opening in the

pivot-bearing to admit segments to be inserted into the space formed by said grooves to form a segmental ring, said segments being provided with internally-screw-threaded openings to facilitate their removal, and a screw-threaded plug for closing the opening in the pivot-bearing, substantially as described.

In testimony whereof I have hereunto set my hand in presence of two subscribing witnesses.

GUSTAV EHRHARDT.
